SAFETY DRILL

John Strother, Rome, N. Y.

Application April 27, 1944, Serial No. 532,990

2 Claims. (Cl. 192—129)

1

The invention relates to a drill attachment, and more particularly to a safety device for drills.

The primary object of the invention is the provision of a device of this character, wherein the control for a drill can be guarded so as to prevent accidental working thereof, for safety purposes, the device being readily moved to a position for the free actuation of the control for the automatic driving of the said drill when required.

Another object of the invention is the provision of a device of this character, wherein it is located on the drill in a position for easy manipulation thereof for safety purposes, so that the drill will not prematurely operate, the device being a releasable guard for the control trigger or other control medium for the starting and stopping of such drill.

A further object of the invention is the provision of a device of this character, wherein the same is adaptable for fluid or electrically driven drills of standard constructions, and when such drill is brought to rest, it cannot be accidentally set in motion, which might result in injury to an operator or damage to a piece of work.

A still further object of the invention is the provision of a device of this character, wherein for the mounting of the same upon a drill avoids the necessity of any alteration in its standard construction, and is in a convenient position for handy manipulation thereof at all times, so that such drill cannot operate until a selected time by a user thereof.

Since it is possible for a safety device of this character to be moved accidentally to a position which would free the squeeze trigger of a drill, I also provide as one of the improved features of my invention, positive means in the form of a spring for normally holding the safety device in such position that the trigger cannot be operated, and which necessitates that the safety device be positively and purposely moved to open position against the tension of the spring.

A still further object of the invention is the provision of a device of this character, which is simple in construction, thoroughly reliable and efficient in operation, readily and easily operated, possessing few parts, durable, easily installed, and inexpensive to manufacture.

With these and other objects in view, the invention consists in the features of construction, combination and arrangement of parts as will be hereinafter more fully described, illustrated in the accompanying drawings, which disclose the preferred and modified forms of the invention,

2

and pointed out in the claims hereunto appended.

In the accompanying drawings:

Figure 1 is a side elevation of a drill showing the device constructed in accordance with the invention applied and in unlocked position.

Figure 2 is a fragmentary sectional view taken on the line 2—2 of Figure 1 looking in the direction of the arrows.

Figure 3 is a fragmentary sectional view taken 10 on the line 3—3 of Figure 1 looking in the direction of the arrows.

Figure 4 is a view similar to Figure 1 showing the device in locking position.

Figure 5 is a view similar to Figure 1 showing 15 a modification.

Figure 6 is a fragmentary side view of a further modification.

Figure 7 is a perspective view of the guard part of the device shown in Figure 1.

Figure 8 is an exploded perspective view showing the guides of the device.

Figure 9 is a perspective view of the guard part shown in Figure 5.

Figure 10 is a side elevation of a drill, partly 25 fragmentary, wherein I have shown another form of my invention in the nature of a keeper or guard above the squeeze trigger so that it cannot be accidentally depressed.

Similar reference characters indicate corresponding parts throughout the several views in 30 the drawings.

Referring to the drawings, particularly Figures 1 to 4, 7 and 8, inclusive, A designates generally an electrically driven hand controlled drill 35 of any standard construction, having a push button control medium 10, for a normally open electric switch 11 in an electric current supply to an electric motor (not shown) as built within the drill A for driving its rotary bit 12, as usual.

As is ordinary in drills of one standard type, there is provided a squeeze trigger 13, which is pivoted at 14 to overhang the button control medium 10, so that when the hand grip 15 of the drill is grasped in the hand of an operator the trigger can be finger actuated to depress the button control medium 10 for the closing of the switch 11 whereby the electric current will be turned on for the driving of the drill or the setting thereof in motion, the switch 11 being opened 45 under spring action when pressure is released from the button control medium 10, as is customary.

Arranged at opposite sides of the control medium 10 is a pair of spaced parallel channeled 50 guide rails 16 for a slidably safety cap 17, these

constituting the device forming the subject matter of the present invention. This cap 17 is closed at its top, sides and one end, while the opposite end next to the medium 10 is open, and extending laterally from the bases of the closed sides of the cap are flanges interfitting the channels in the rails 16, the cap 17 being adapted to be manually shifted for confining within the same the medium 10 beneath the trigger 13, to eliminate the possibility of depressing such medium for the closing of the switch 11 accidentally. When the cap 17 is moved clear of the control medium 10, the same can then be actuated by the trigger 13 for the closing of the said switch.

Since it might be possible, under certain circumstances, for the safety cap 17 to be moved from beneath the squeeze trigger 13, I provide a spring 24 between guide rails 16 and retained in position by a keeper 25, which spring presses upon the cap 17 to hold it normally in locking position beneath the squeeze trigger. In practice, the safety cap must be moved out from under the squeeze trigger positively and intentionally against the action of spring 24.

In Figures 5 and 9, of the drawings, there is shown a modification, wherein the trigger guard 19 for the trigger is located at the under side of the barrel of the drill, next to the grip 20, and to this under side is slidably fitted the cap 21 similarly to the fitting of the cap 17 hereinbefore set forth. This cap 21 is moved over the guard 19, so that the trigger within the same cannot be accidentally operated for rendering the drill active.

A spring 24A and a keeper 25A is provided to maintain the cap 21 positively in position over the guard 19 so that the trigger cannot be operated unless the cap is intentionally pushed into the open position against the spring.

In Figure 6 of the drawings there is shown a further modification of the invention, wherein a blocking wedge 22 is slidably fitted on the drill A in the path of the trigger 23 and this wedge is movable under and from under such trigger, the wedge 22 when under the trigger 23 being effective for blocking operation thereof to avoid depressing the control medium of the kind hereinbefore described, so that such drill will not be set in motion.

The spring 24B and keeper 25B are in all re-

spects similar to springs 24 and 24A and keepers 25 and 25A.

In Figure 10, I have shown another modified form of my invention wherein a guard 27 having a horizontal position 28 and a vertical support 29 is provided which overhangs the squeeze trigger 13 and prevents pressing of the same. The support 29 is slidable between rails 16 and is urged in its closing or guarding position by spring 24C retained by keeper 25C.

What is claimed is:

1. A safety device for an automatically driven drill having a power energy control medium, comprising a sliding safety cap closed at its top, sides and one end and laterally extending flanges formed integral with the bases of said closed side, for blocking the actuation of the said medium, and channelled rails slidably fitting said laterally extending flanges of said safety cap upon the drill for movements thereof to blocking and non-blocking position.

2. A safety device for an automatically driven drill having a power energy control medium, comprising a sliding safety cap closed at its top, sides and one end and laterally extending flanges formed integral with the bases of said closed side, for blocking the actuation of the said medium, and channelled rails slidably fitting said laterally extending flanges of said safety cap upon the drill for movements thereof to blocking and non-blocking positions, the last named means locating the first named means for reach of an operator when hand gripping the drill.

JOHN STROTHER.
